NO DRA

No. 8774 X

PATENTED

Apel 22

1895

Allen Beldner

Improvement in Fur Substitute for Deerskin and Sheepskin

DESCRIPTION:

CLAIM:

In manufacturing a fur cloth or fitting in such a manner of wool and fur combined or entirely of fur and of such size and shape as may be necessary in order to make a valuable and elegant substitute for most of the different kinds of fur skins and peltry
now in use.